UNITED STATES PATENT OFFICE.

JOHN McGAFF, OF CHICAGO, ILLINOIS, ASSIGNOR OF ONE-HALF TO INTERSTATE IRON AND STEEL COMPANY, OF CHICAGO, ILLINOIS, A CORPORATION OF ILLINOIS.

BUSHELING FURNACE.

Application filed March 31, 1921. Serial No. 457,259.

To all whom it may concern:

Be it known that I, JOHN McGAFF, a citizen of the United States, residing at Chicago, in the county of Cook and State of Illinois, have invented certain new and useful Improvements in Busheling Furnaces, of which the following is a specification.

My invention relates to furnaces for busheling scrap metal, and consists in the 10 matters hereinafter described and then pointed out in the appended claims.

The purpose of my invention is to provide an improved oscillating chamber in which the heat-softened charge of scrap is 15 hammered or compressed into welded condition by being bodily dropped from end to end of the chamber, thereby hammering and consolidating the particles and welding them into a dense and compact ball or bloom. 20 The principal object is to provide the hearth with which the metal under treatment contacts in the operation of the chamber with improved means to retain a lining or bed of metallic oxides or slag which while preventing the burning or melting of the plates 25 also furnishes a clean and homogeneous working surface containing no substances harmful to the metal, so that the resulting ball or bloom is uniform and homogeneous. 30 A further object is to provide improved means for mounting the oscillating chamber, and other advantages will appear from the disclosure.

In the accompanying drawings showing 35 an embodiment of the several features of my invention, Fig. 1 is a view in elevation of the furnace showing one end of the chamber with the fire-box and stack-flue on opposite sides;

40 Fig. 2 is a view partly in side elevation and partly in section on the line 2—2 of Fig. 1;

Fig. 3 is a sectional view on the line 3—3 of Fig. 1;

45 Fig. 4 is a longitudinal sectional view of the hearth of the chamber with the upper portions of the ends broken away;

Fig. 5 is a top plan view of the bottom 50 with its lining omitted on the line 5—5 of Fig. 4;

Fig. 6 is a longitudinal sectional view of an end-gate, and

Fig. 7 is a view of the inside face of the same.

55 The metal-working chamber is an oblong

trough composed of opposite side plates 1, opposite end-plates 2, a top plate 3, and a bottom 4, all being of cast iron and rectangular in outline. The top and sides and bottom are united at their meeting edges 60 by having their external flanges riveted or bolted together, and all extend parallel with the longitudinal or major axis of the chamber to form an elongated or rectangular chamber, preferably seven or eight feet in 65 length and about three feet in width and about three and one-half feet in height in practice. The end-plates are similarly bolted or riveted in place and preferably are of suitable size and shape to close only 70 part of the ends of the chamber to leave an arched opening at the lower portion of each end. A sliding gate or door 5 closes each of the openings when the furnace is in operation, being movably mounted in guides 75 or keepers 6 and having a peep-hole 7 near the upper end if desired. While one of the end-plates may entirely close or cover its opening, I prefer to employ an opening at 80 each end of the chamber so that one may be used for charging it with a fresh batch of material when the other is used to discharge the welded bloom or ball. The end doors or gates are concave on their inner surfaces to center the mass of metal in the median 85 line of the chamber as it moves back and forth from end to end thereof, the end walls being correspondingly curved.

Each side plate or wall has a central circular opening 8, one to admit heat from the 90 fuel combustion chamber 9, located at one side of the welding chamber, and the other for the exit of the gases and other products of combustion to the flue or stack 10 located at its other side.

The chamber is turned on its transverse or minor axis as the center of movement, so that its ends alternately rise and fall. It is preferably oscillated, and for this purpose is carried in a cradle composed of two segmental rockers 11, arranged on its opposite sides and connected to it by any suitable means, such as the supporting spokes 12 and arms 13. The rockers travel upon flanged supporting rollers 14 which are arranged in the arc of a circle corresponding to the curvature of the rockers and are journaled in bearings in the base or foundation 15. The cradle is rocked by suitable power mechanism represented by 16; in the 100 105 110

illustrative example the driving pinion 17 engages a toothed sector or rack 18 carried by one of the rockers. By supporting the chamber in a cradle I do away with trunnions or bearing at the central openings 8, and so am able to make these opposite openings of greatly increased size, in area about one-third of the sides, to increase the volume of the flame or heat passing through 5 the chamber and also the amount of the working surface of the chamber directly exposed to it.

The top and sides of the chamber and the upper portions of the ends where the parts 15 are subjected only to heat are lined with refractory brick 19. The hearth, formed by the bottom and the lower parts of the ends with which the metal under treatment contacts as it travels back and forth by gravity 20 from end to end of the chamber when it is oscillated or rocked, is provided with means to retain a bed or lining of slag or oxides to form the working surface for the metal. For this purpose I cast the bottom with a 25 series of dove-tailed or undercut recesses or pockets 20 extending transversely of the trough and path of travel of the charge therein. In practice a quantity of cinder pig is charged onto the bottom to fill the 30 pockets and form a bed of about two inches in thickness upon the bottom, and it is then melted to form a solid lining of slag 21 which is superposed on the bottom and interlocked with it by its keys 22 lying in the 35 cross-pockets as shown in Fig. 4. By this construction the bottom plate itself forms the box or support on which the cinder is charged and held while being melted to form the lining, and after the slag cools it 40 forms a lining that is interlocked with the bottom transversely to the line of travel of the metal and so braced and strengthened across or against its thrusts or blows. In 45 practice I prefer to make the bottom 4 in sections as shown in Figs. 4 and 5, to reduce the liability of warping and so that if any part becomes warped or worn it may be readily removed and replaced without disturbing other parts, and in such cases the 50 sections are provided with overlapping joints 23 at their meeting edges.

The lower portion of the inner faces of the doors upon which the metal hammers and beats as it reaches each end of its drop 55 is cast with flanges 24 and 25 to form retaining pockets to similarly hold an oxide or slag lining 26 to prevent the metal under treatment from coming into contact with the cast-metal of the doors. These pockets are 60 formed by casting them into the inner faces when the doors are made, and as the stress or impact of the metal is substantially in line with them they may be of any suitable shape and contour, such for example as the plain 65 ones shown. In practice they need extend

over only the lower half of the door as the metal will not extend above this point when it strikes the door; if either end-plate entirely closes its end of the chamber its lower portion will be similarly provided with 70 retaining pockets. By employing the end-pockets to retain a lining of slag or oxides I am able to utilize the ends to hammer or compress the metal to weld its particles without burning the ends or poisoning the 75 charge. The outer faces of the doors are provided with strengthening ribs 27 to enable them to better resist the impact or blows of the metal upon them when the chamber is in operation.

The slag bed or lining prevents the burning or melting of the hearth and affords a clean and homogeneous working surface for the metal to travel over and strike so that no impurities get into the mass to prevent a 80 perfect weld. By this means I obviate the objection arising from the use of magnesite brick or similar refractory materials heretofore employed for lining the working surface and in which the particles of such foreign and neutral materials scraped off by the abrading action of the charge mixed with the metal and acted as an impurity to prevent it from welding either in the scrap furnace itself or in the subsequent "squeezing" treatment. By the present invention there is nothing in the working surface to harm the metal or prevent it from welding, and so it will form a refined and homogeneous bloom or ball. Also, by arranging the grooves in 85 an imperforate bottom this part itself acts as the box for the molten cinder in the preparation of the slag-lining, and then as a base to which the hardened lining is keyed and interlocked across or transverse to the path of travel of the moving mass of metal to offer effective resistance to its strains and 90 stress.

In operation, after the hearth is lined the chamber suitably pre-heated is charged with 100 a mass of scrap iron or steel, and after being closed is oscillated by the power mechanism so that its ends alternately rise and fall, heat passing into it to bring the charge to welding temperature. The oscillation of the oblong chamber to an angle of 40 to 50 degrees causes the charge to pass back and forth from end to end of the hearth a distance of seven or eight feet, and at the rise of each end the charge is bodily displaced therefrom and drops by gravity the length of the chamber against the opposite end, and being entirely displaced from one end before striking the other end it attains considerable momentum and hammers against the latter with 110 great force, and as the chamber is oscillated the particles of softened metal are consolidated and compressed by its repeated blows against the ends so that the mass is welded 115 into a ball or bloom of compact iron or steel 120 125 130

as the case may be. The heated scrap is hammered and beaten into intimate and permanent union by its impacts or blows on the ends of the chamber, and after the welding is completed the chamber may be tilted down at one end and the door opened to discharge it, while it may receive another charge at the same time through the opposite door without altering its position with respect to the co-acting parts of the furnace. As the welding is accomplished in the chamber the ball or bloom is ready for use when discharged, any additional and separate step of passing it through the squeezers being merely to shape it for the first pass in the rolls.

I claim:

1. A busheling furnace comprising an oblong trough-shaped chamber having a flat bottom extending in the direction of its major axis and consisting of an imperforate plate having cross-pockets, the sides having opposite openings communicating respectively with a source of heat and a flue, and means to oscillate the chamber to alternately raise and lower its ends.
2. A busheling furnace comprising an oblong trough-shaped chamber having a hearth consisting of an imperforate bottom and end walls, the bottom having undercut transverse slag-pockets and the ends having slag-pockets at their lower portions, means connecting the chamber with a source of heat and a flue, and means to oscillate the chamber to alternately raise and lower its ends.
3. A busheling furnace comprising an oblong chamber having longitudinal sides, a flat bottom and angular ends, the bottom

having slag-pockets extending transversely to the line of travel of the metal, the sides having opposite openings communicating respectively with a source of heat and a flue, the heat-opening extending near to the chamber bottom, and means to oscillate the chamber on its minor axis.

4. A busheling furnace comprising an oblong chamber having longitudinal sides, a flat hearth and angular ends, gates at the ends, the hearth having slag-pockets extending transversely to the line of travel of the metal thereon and the gates having slag-pockets disposed at their lower portions, the sides having opposite openings communicating respectively with a source of heat and a flue, and means to oscillate the chamber on its minor axis to cause the metal to drop by gravity the length of the hearth alternately from one end gate to the other.

5. A busheling furnace comprising an oblong chamber having longitudinal sides, a flat hearth and angular ends having openings at their lower portions, concave gates closing the openings in the ends, the hearth having slag-pockets extending transversely to the line of travel of the metal thereon and the gates having slag-pockets disposed at their lower portions, the sides having opposite openings communicating respectively with a source of heat and a flue, and means to oscillate the chamber on its minor axis to cause the metal to drop by gravity the length of the hearth alternately from one end gate to the other.

JOHN McGAFF.
